Primary Examiner — Wan Laymon*Assistant Examiner* — Clint A Samuel(74) *Attorney, Agent, or Firm* — Ward and Smith, P.A.;
Ryan K. Simmons(57) **CLAIM**

The ornamental design for a closeable container, as shown and described.

DESCRIPTION

FIG. 1 is a perspective view of a closeable container showing a new design;

FIG. 2 is a front view thereof;

FIG. 3 is a rear view thereof;

FIG. 4 is a left side view thereof, the right side being a mirror image;

FIG. 5 is a top view thereof;

FIG. 6 is a bottom view thereof;

FIG. 7 is a perspective view of the closeable container showing the closeable container in an open configuration;

FIG. 8 is a plan view of the closeable container showing the closeable container in a blank configuration;

FIG. 9 is a perspective view of a closeable container in accordance with a second embodiment of the invention;

FIG. 10 is a front view thereof, the rear being a mirror image;

FIG. 11 is a left side view thereof, the right side being a mirror image;

FIG. 12 is a top view thereof; and,

FIG. 13 is a plan view of the closeable container showing the closeable container in a blank configuration.

The broken lines shown in the figures are included for the purpose of illustrating perforations and forms part of the claimed design.
